dale, N. Y.

Application January 17, 1935, Serial No. 2,174

4 Claims. (CL. 58—38)

My present invention relates to a time keeping mechanism and more particularly to an improved striking mechanism for a motor driven timing train.

In my co-pending application, Serial Number 695,699 filed October 28, 1933, now Patent No. 2,058,609 granted Oct. 27, 1936. I have described and claimed an improved striking mechanism for motor driven timing trains, such mechanism including an operating circuit and switches contained therein and forming an essential part thereof.

My present invention is to be considered as an improvement over the invention described and claimed in my copending application above identified, and comprises an improved striking mechanism for a motor driven timing train, wherein the striking mechanism and the operating mechanism therefor are entirely mechanical and the use of an electrically operated mechanism with the pertinent switches therefor is entirely eliminated.

In carrying out my present invention I associate the striking mechanism with the timing train so as to have the striking mechanism operated by power derived from the timing train motor and in accordance with a mechanism directly controlled by the timing train and wherein the usual snail-cam is employed.

An important feature of my invention therefore, is an improved striking mechanism for a time keeping clock.

Another feature of my invention resides in the construction of a striking mechanism for a motor driven clock wherein the striking mechanism and the operating mechanism therefor is entirely mechanical.

In carrying out the latter feature of my invention, I provide on the timing train a device operated in synchronism therewith, and which automatically sets at any predetermined period, a snail-cam which determines the setting of an arcuate ratchet, which in turn is propelled by a step-by-step device operated and controlled by the timing train. In connection with the timing train is also a cam member which automatically, and at predetermined intervals of time, sets the arcuate ratchet to initiate the striking of the half hour periods. Associated with the arcuate ratchet and with the driving mechanism therefor, is an intermediate device for intermittently releasing the striking hammer which therefore intermittently sounds the striking mechanism in accordance with the predetermined setting of the arcuate ratchet.

A further feature of my invention is an improved means for maintaining the arcuate ratchet in its uppermost position from the end of one complete revolution of the snail-cam to the beginning of the next revolution thereof.

Other features of my invention will be referred to in the description of a preferred embodiment of my device.

In the accompanying drawings:

Fig. 1 is a front elevation of a synchronous motor time keeping and striking mechanism embodying my invention.

Fig. 2 is a rear elevation of a clock case showing my invention housed therein.

Fig. 3 is a side elevation of the structure shown in Fig. 1.

Fig. 4 is an enlarged sectional side elevation of my improved synchronous motor rotating element.

Referring to the drawings, 10 designates a front plate and 11 a back plate, arranged parallel to each other, and held in parallel-spaced relation with respect to each other by a plurality of posts 12. The elements 10, 11 and 12 constitute a framework, in and on which are mounted the various elements constituting a time keeping and striking mechanism embodying my invention. Secured to one end of the posts 12, are lugs or ears 13, and by means of which the framework may be secured in a case 14. Rotatably mounted in suitable bearings or bushings, to be hereafter described, and in the plates 10 and 11 is a "second" shaft 15 which carries an indicating hand 16 at its outer end, or the end that projects outwardly from the front plate 10.

Rotatably mounted on the "second" shaft 15 is a hollow "minute" shaft 17 which carries at its outer end a minute hand 18. Rotatably mounted on the hollow "minute" shaft 17 is a hollow "hour" shaft 19, such "hour" hand 19 carrying at its outer end the "hour" hand 20. The shafts 15, 17 and 19 have a common axis and the outer bearing for the "hour" shaft 19 is mounted in the front plate 10 of the framework above referred to. The shafts 15, 17 and 19 are equipped with various mechanisms which will be hereinafter particularly described.

Mounted in suitable bearings in the front and rear plates 10 and 11 respectively, such bearings being in alignment with each other, is a drive shaft 21. The shaft 21 extends outwardly beyond the back plate 11 and secured to this extension is a gear 22. Secured to the back plate 11, as by staking, or in any other convenient manner, is a hub 23 and securely mounted in the hub 23 and

- extending outwardly from the plate 11, or to the right as shown in Fig. 3, is a shaft 24. Rotatably mounted on the shaft 24 is a bearing hub 25 of the rotatable element of a synchronous motor. Referring to Fig. 4 it will be noted that the rotatable hub 25 has a reduced end 26, and frictionally secured on the reduced end is a cup-shaped member 27. Preferably formed integral with the cup-shaped member 27 and intermediate 10 the ends thereof is an annular flange 28. Again referring to Fig. 4 it will be noted that there is mounted on the right hand end of the cup-shaped member 27, and abutting against the annular flange 28, a laminated armature 29, which forms part of the rotating element of the synchronous motor. Rotatably mounted on the front and left hand portion of the cup-shaped member 27, as viewed in Fig. 4, and abutting against the annular flange 28 is a circular disc 30. The function and operation of this circular disc will be hereafter more fully described. Frictionally engaging with the outer open end of the cup-shaped member 27 is a second cup-shaped member 31, the outer open end of which is spaced apart from the disc 30. Between the cup-shaped member 31 and the disc 30 is arranged a spring washer 32 having a plurality of arms 33 extending radially outward therefrom, and the outer ends of these arms engage with one surface of the disc 30, and automatically hold such disc against the annular flange 28. Formed integral with, and extending outward from, the main portion of the cup-shaped member 31 is a shaft 34 provided on its outer end with a knob 35 or other member 35, and by means of which the shaft 34 and therefore the cup-shaped members 31 and 27 and parts attached thereto may be rotated. The reduced end 26 of the hub 25 is provided with a plurality of passages 36 communicating with the bearing extending through the hub 25 and in which bearing is located the shaft 24. The cup-shaped member 27 and 31 constitute a practically sealed chamber which may be filled with any suitable lubricant, and 45 which will furnish lubricant to the shaft 24 in its bearing for practically the life of the device. The rotating element shown in Fig. 4 and above described is associated with spaced laminated pole pieces, such laminated pole pieces being mounted on the rear of the plate 11 by spacing blocks 38. At the end of the laminated pole pieces, remote from the rotating element above described, is a laminated cross bar 39, on which is mounted the energizing coil 40, which takes power from any convenient alternating current source. On the hub 25 are formed teeth constituting a pinion which engages with and drives the gear 22, above referred to as being attached to the extension of the shaft 21. 50 Rotatably mounted in aligned bearings in the plates 10 and 11, and arranged parallel to the shaft 21 is a shaft 42. Secured to the shaft 42 is a link 43 provided at one end with a groove or slot 44 which is engaged by a cam 45, secured 55 to the shaft 21. Also secured to the shaft 42 at a point adjacent to the plate 11 is a link 46. Referring to Fig. 1 it will be noted that at the lowermost end of the link 46 is pivotally mounted the lower end of a driving pawl 47, and associated 60 with the pawl 47 is a helical spring 48 which tends to rotate the pawl in a clockwise direction. Again referring to Fig. 1 it will be noted that at the upper end of the link 46 is pivotally mounted a driving pawl 49, and associated with such 70 pawl is a helical spring 50 which also tends to

rotate the pawl 49 in clockwise direction. Secured to the "second" shaft 15 is a ratchet 51, with which both of the driving pawls 47 and 49 engage. It will be obvious that as the shaft 21 is constantly rotated under the influence of the 5 rotating element in the synchronous motor above described, the "second" shaft 15 will be intermittently rotated in a clockwise direction by the driving pawls 47 and 49, and the use of such pawls on the ratchet will simulate the ticking of the 10 usual spring driven clock. It will be noted that with respect to the ratchet 51, no holding pawl per se is necessary, as the driving pawls 47 and 49 alternately act in such capacity.

Secured to the "second" shaft 15, and lying 15 adjacent to the ratchet wheel 51, is a cam 52 which engages with a slot 53 formed in one end of an arm 54. Such arm is pivotally mounted at one end remote from the slot 53 on one of the posts 12. An oscillatory movement of the arm 20 54 about the post 12 as a pivot is therefore imparted by the rotative movement of the cam 52, which as above noted is carried by the "second" shaft 15. Intermediate the ends of the arm 54 is pivotally mounted a driving pawl 55, and associated with the driving pawl 55 is a helical spring 56, which tends to rotate such pawl in a clockwise direction. The driving pawl 55 engages with a ratchet 57 attached to the "minute" shaft 17 and the "minute" shaft 17 is therefore rotated 25 with a step-by-step movement in a clockwise direction. Secured to and extending between the plates 10 and 11 is a shaft 58, and rotatably mounted on such shaft is a holding pawl 59 which engages with the minute ratchet 57. A helical spring 60, associated with the holding pawl 59, holds such pawl in operative engagement with the ratchet wheel 57.

Secured to the "minute" shaft 17 is a pinion 61, which meshes with and drives a gear 62 40 rotatably mounted on a stub shaft 63 secured to the inner face of the front plate 10. Secured to the gear 62 and also concentric with the shaft 63 is a pinion 64 which meshes with and drives a gear 65 that is secured to the "hour" shaft 19. 45

The relation between the second ratchet 51, the minute ratchet 57, the gear 65, and the speed of rotation of the shaft 21 is such that the "minute" shaft 17 makes one complete revolution every hour, the "hour" shaft 19 one complete revolution every 12 hours, and the "second" shaft 15 one complete revolution every minute.

The above describes the timing train operated by a synchronous motor. Associated with such timing train is a striking mechanism. Such 55 striking mechanism is controlled by devices secured to or associated with the timing train and which devices operate in synchronism with the timing train, in order that the striking may take place at the proper times and bear a proper relation to the time indicated by the timing train.

The means directly associated with the timing train for controlling the operation of the striking mechanism is the well known snail-cam 66, which cam is provided with a series of steps 67, 68 etc. 65 and such cam is mounted on the "hour" shaft 19. As an auxiliary device associated with the timing train I have mounted on the "minute" shaft 17 a cam 69, which cam is provided with radially disposed indentations 70, and the purpose of these indentations, or the surfaces defining the same, will be apparent as the description of the invention progresses.

Rotatably mounted in aligned bearings in the front and rear plates 10 and 11 respectively, is a 75

shaft 170. One end of this shaft 170 extends outwardly upon the front plate 10, and secured to this extending end is an arm 71. This arm 71, at its outer end, has formed integral therewith an arcuate ratchet member 72. On the arm 71, intermediate the ends thereof, is a laterally extending pin 73 which is adapted to engage with the various steps 67, 68 etc. formed on the periphery of the snail-cam 66. The pin 73 on the arm 71, in its engagement with the various steps 67, 68 etc. of the snail-cam 66, determines the extent of downward movement of the arcuate ratchet member 72, and thus, as will be hereinafter explained, determines the number of blows 10 emitted by the striking mechanism. The pin 73 on the arm 71, in its engagement with the steps of the snail-cam 66, determines the striking of the hours indicated by the timing strain heretofore described, and in addition to these means I 15 have provided auxiliary means for determining the setting of the arcuate ratchet 72 for the purpose of determining the striking of the half hour 20 periods.

This latter device consists of the following. Secured to the shaft 170, intermediate the ends thereof, is an arm 74 which lies substantially parallel to but spaced apart from the arm 71. On the cam 69 are laterally extending pins 75 and 175 respectively, which in the rotative movement 25 of the cam 69 engage with the arm 74 and thus determine not only the setting of the arcuate cam 72 for the purpose of initiating the striking of the half hour periods, but also maintain the pin 73 in its uppermost position after the striking of 30 the half hour following noon until the cam 67 35 designating one o'clock, has moved into a position beneath such pin 73.

The normal position of the arcuate ratchet 72 is determined by the engagement of the pin 73 with one or the other of the cams 67, 68 etc.

At the end of the link 43 remote from the slot 44 is pivotally mounted the lower end of a driving pawl 76, which pawl engages with the teeth in the arcuate ratchet 72, and on the oscillation of 45 the link 43 steps the arcuate ratchet 72 upward from the position shown in Fig. 1 to its uppermost position.

Mounted in aligned bearings in the front and rear plates 10 and 11 respectively is a shaft 77, and secured to this shaft is a sleeve 78, to which 50 is attached one end of a pawl 79, and which pawl engages with the teeth in the arcuate ratchet 72 and acts as a holding pawl therefor. A helical spring 80 on the shaft 77, and cooperating with 55 the holding pawl 79, tends to rotate such holding pawl in a counter-clockwise direction, and into position to be in engagement with the teeth of the arcuate ratchet 72. Immediately preceding the striking operation, both the driving pawl 76 and 60 the holding pawl 79 are released from the teeth of the arcuate ratchet 72, which thereupon falls from its uppermost position into a position determined by the engagement of the pin 73 with one or the other of the steps 67, 68 etc. of the snail-cam 66 and/or by the engagement of the arm 74 with the pins 75 and 175 respectively carried 65 by the cam 69.

The striking operation therefore takes place on the upward step-by-step movement of the arcuate ratchet 72 because of the intermittent engagement thereof by the driving pawl 76.

The release of the driving pawl 76, and the holding pawl 79, from the arcuate ratchet 72, is performed by the following instrumentalities and 75 in the following manner. Rotatably mounted in

aligned bearings in the front and rear plates 10 and 11 respectively, is a shaft 81. Secured to such shaft 81 is an arm 82 which extends generally downward, as viewed in Figs. 1 and 3, and has its lower end cooperating with the cam plate 69. Secured to the shaft 81 is a hub 83, and secured to such hub 83 and extending downwardly therefrom is a resilient member 84. This resilient member 84 extends downwardly, and as the shaft 81 is rotated, for example in a counter-clockwise 10 direction, as viewed in Fig. 1, the holding pawl 79 and the driving pawl 76 for the arcuate ratchet 72 lie in the path of movement of the lower end 15 of the resilient member 84. Therefore upon rotation of the shaft 81 in the direction noted, it is apparent that the resilient member 84 will engage with the driving pawl 76 and holding pawl 79, and will move them out of engagement with the teeth of the arcuate ratchet 72, thus allowing such arcuate ratchet to drop from its uppermost 20 position into a position as determined either by the cooperation of the pin 73 with one or the other of the steps 67, 68 etc. of the snail-cam 66 and/or the engagement of the pins 75 and 175 respectively with the arm 74. The lower end of 25 the arm 82 is always in engagement with the cam plate 69, and thus follows the contour of such cam plate, including those surfaces which define the openings 70 in such cam plate.

Assume that the apparatus is in the position 30 indicated in Fig. 1, and therefore, that the lower end of the arm 82 is in engagement with the edge of the cam plate 69, and for the moment is located at the bottom of one of the cutouts 70. As the cam plate 69 rotates in the direction of the arrow 35 shown in Fig. 1, that is in a clockwise direction, it is obvious that the end of the arm 82 will ride up on the curved edge of the cam plate 69 defining one side of the cutout 70 and therefore, the lower end of the arm 82 will move to the 40 right as shown in such Fig. 1, thereby rotating the shaft 81 in a counter-clockwise direction, and simultaneously moving the lower end of the resilient member 84 to the right and into engagement with the driving pawl 76 and holding pawl 45 79.

Rotatably mounted in aligned bearings in the front and rear plates 10 and 11 respectively is a shaft 85. Secured to such shaft and extending radially outward therefrom is an arm 86. The outer end of this arm 86 is normally in engagement with the upper end of an arm 87 secured to, and extending upwardly from, the shaft 77. Secured to the shaft 85 is a hub 88 and attached 50 to such hub 88 is a resilient striking rod 89, provided with a striking hammer or similar instrument 90 at its lower end. Secured to the shaft 42, and extending upwardly therefrom, is an arm 91, the upper end of this arm being adapted to be brought intermittently into engagement with 55 the resilient member 89 for a purpose to be hereinafter described. Secured to the shaft 81 is an arm 92, which upon rotation of the shaft 81 in a counter-clockwise direction engages with the arm 86 and lifts the same out of engagement with the 60 end of the arm 87.

The relation of the arm 86 with respect to the arm 87 is such that the holding pawl 79 may remain in engagement with a tooth of the arcuate ratchet 72 upon rotation of the shaft 77, after 70 the upper end of the arm 87 has moved out of engagement with and from beneath the end of the arm 86. Associated with the striking rod 89, and striking hammer 90, for the purpose of sounding the time is any convenient sound emitting device, 75

such for example as the metallic rod 93 securely anchored in a block 94 or other suitable base.

The striking operation takes place as follows:

- Referring to Fig. 1, it will be noted that the pin 73 is in engagement with the lowest step of the snail cam 66, or in other words the arcuate cam 72 has been permitted to fall into a position to cause 12 o'clock to be struck by the striking mechanism. It is understood of course, that the mechanism shown in Fig. 1, and particularly the cam disc 69 and snail cam 66, are rotating in a clockwise direction, or in the direction of the arrow shown in Fig. 1. As shown in Fig. 1 the radially extending edge or face 95 of the cam disc 69 has just passed beyond the lower end of the arm 82 which is attached to the shaft 81, and the arm 82 therefore has fallen into the depression 70 in such cam disc 69, thus rotating the shaft 81 in a clockwise direction, and bringing the arm 92 downwardly out of engagement with the end of the arm 86; bringing the resilient member 84 to the left away from the driving pawl 76 and the holding pawl 79; allowing such driving and holding pawls respectively to be brought into operative position with respect to the arcuate ratchet 72. The upper end of the arm 81 therefore assumes its proper position under the end of the arm 86, thus holding for the moment the striking member 89 and hammer 90 in inoperative position, and in the position shown in such Fig. 1.

It being understood that the driving shaft 21 is constantly rotating, it is obvious that the link 43 is constantly oscillating, together with the shaft 42 and all parts attached thereto, and that because of the position of the cam 45 in the slot 44 the next movement of the link 43 will result in a downward motion of the end of such link, to which the lower end of the driving pawl 76 is pivotally attached. Therefore the driving pawl 76 will move downward and its upper end will engage in the next lowermost tooth of the arcuate ratchet 72. Simultaneously with such movement the arm 91 is oscillated, because of the oscillation of the shaft 42, and the upper end thereof will engage with the member 89, thus rotating the shaft 85 in a counter-clockwise direction, and moving the outer end of the arm 86 upwardly so as to permit the upper end of the arm 81 to be positioned thereunder, if such movement has not already taken place.

The link 43 continuing its oscillatory movement, the next step will be an upward movement of the driving pawl 76 which will move the arcuate ratchet 72 upwardly about the shaft 170 through the space of one tooth and in such movement the upper end of the holding pawl will ride up on the tooth with which it happens to be at this time in engagement, thus rotating the shaft 77 in a clockwise direction, and moving the upper end of the arm 81 out from under the end of the arm 86. Immediately such arm is freed, the weight of the arm 86, together with the weight of the hammer 90, and the member to which it is attached, will rotate the shaft 85 in a clockwise direction and the hammer 90 will engage with the sound emitting element 94, thus striking one blow.

By this operation the end of the holding pawl 79 has come into position under the face of the first uppermost tooth of the arcuate ratchet 72, and the arcuate ratchet 72 will thus be held in the position to which it has been moved by the driving pawl 76. The driving pawl is now moved downward and the arm 91 rotated to the right thus moving the arm 89 to the right, and rotat-

ing the shaft 85 so as to move the end of the arm 86 into the position now shown in Fig. 1. During this movement the end of the arm 86 necessarily contacts with the side or inner face of the arm 87, as viewed in Fig. 1, thus slightly rotating the shaft 77 in a clockwise direction, and causing a slight outward movement of the upper end of the holding pawl 79 with respect to the tooth of the arcuate ratchet 72 with which it is in engagement.

This outward movement of the upper end of the arm 87 however, is insufficient to remove the upper end of the holding pawl 79 from engagement with the tooth of the arcuate ratchet 72, and therefore the parts are again in the position shown in Fig. 1. This sequence of operations is repeated, the arcuate ratchet 72 moving upward step-by-step through the space of one tooth at each step, and at each step the hammer 90 engages with the sound emitting device 94, until the arcuate ratchet 72 reaches its uppermost position, when the striking stops. The driving pawl 76 is subjected to an intermittent motion during the operation of the timing train, but after the arcuate ratchet 72 reaches its uppermost position no further motion will be imparted to it, as the driving pawl 76 rides on the plain surface 97 of the arcuate ratchet 72.

During this striking operation the cam plate 69 and the snail-cam 66 rotated in a clockwise direction, pin 73 on the arm 71 gradually approaching the practically radial face 94 of the snail-cam 66. With each step upward of the arcuate ratchet 72, a similar step is also imparted to the pin 73, and therefore by the time the last blow is struck by the hammer 90, such pin 73 will be moved radially outward with respect to the axis of rotation of the snail-cam 66 a distance greater than the radial distance of the cam surface 67. During the continued rotation of the cam plate 69, the lower end of the arm 82 also engages the cam surface 98 of the cam disc 69, thus rotating the shaft 81 in a counter-clockwise direction, and moving the end of the arm 92 upwardly into engagement with the end of the arm 86, and such arm 92 holds the arm 86 upwardly, thus putting the striking hammer 90 out of operative condition, regardless of the movement of the arm 81. During the subsequent continued rotation of the cam disc 69, the lower end of the arm 82 will ride on the circumferential edge of the cam plate 69, thus maintaining the arm 86 in its uppermost and inoperative position. Also the resilient member 84 will move into engagement with the driving pawl 76 and holding pawl 79, and the arcuate ratchet 72 will again drop into the position shown in Fig. 1.

The hour having been struck, and the "minute" ratchet 57 rotating in a clockwise direction at the rate of one resolution per hour, before the 30 minute period has elapsed, the pin 75, carried thereby will engage with the arm 74, rotating the shaft 170 in a counter-clockwise direction and raising the arm 74, and arcuate ratchet 72, until the pin 73 on the arm 71 occupies a position one step beneath that to which it was moved on the striking of the previous hour, or in other words, in position for the driving pawl 76 to effectively operate on a single, and the lowermost tooth of the arcuate ratchet 72.

Shortly after the striking of the half hour the end of the arm 82 will ride up on the curved face 98 of the notch 70, thus moving the arm 92 into position to prevent further operation of the striking hammer 90, and also moves the re- 75

silent member 34 into position to release both the driving pawl 76 and the holding pawl 79 from the arcuate ratchet 72. Under ordinary circumstances, and as is the case with every other 5 hour period except the 12 o'clock period just described, the dropping of the arcuate ratchet 72 to its lowermost position brings the pin 73 on the arm 71 into engagement with the cam face, as for example the cam face 67, 68 etc. The pin 73 on the arm 71 after the half hour has been struck—on every hour except the 12 o'clock hour just referred to — will ride on the surface of the step of the snail-cam until the next succeeding hour, when it will drop off onto the next lower cam. 10 At the 12 o'clock period, which has just been described, such a method of operation is impossible, as the 12 o'clock cam is the lowermost cam of the series on the snail-cam 66, and it is necessary therefore, after the striking of the half hour 15 period between 12 and 1 o'clock, to maintain the pin 73 in its uppermost position so as to ride on top of the cam face 67 when the snail-cam 66 rotates a sufficiently great distance. This is accomplished by providing the pin 75 on the 20 minute ratchet 57, and which pin 75 comes into operation after the pin 73. The pin 75 will engage with the arm 74 after such arm has been acted upon by the pin 73, and the arm 74 will be maintained in its uppermost position, and therefore 25 the pin 73 on the arm 71 will be held in a position to ride up to the cam face 67 on the rotation of the snail-cam.

While I have necessarily shown and described the preferred embodiment of my invention somewhat in detail it is to be understood that I may vary the size, shape and arrangement of parts comprising the devices within relatively wide limit without departing from the explanation of the invention.

40 I claim:

1. An improved striking mechanism for a synchronous motor driven time keeping mechanism, comprising a sound emitting device, a pivoted hammer adapted to engage therewith, means for normally holding said hammer in inoperative position, an arcuate ratchet, a snail cam associated with the time keeping mechanism for controlling the setting of the ratchet to determine the number of blows to be struck by the hammer, a driving pawl for intermittently and positively moving the ratchet step-by-step, a holding pawl for maintaining the ratchet in the position to which it has been driven by the driving pawl and for periodically releasing the hammer in accordance 45 with the movement of the ratchet.

2. An improved striking mechanism for synchronous motor driven time pieces, comprising a sound emitting device, a pivoted hammer adapted

to engage therewith to cause a sound emission from said sound emitting device, a lever associated with said pivoted hammer for rotating said pivoted hammer into engagement with the sound emitting device by gravity, an arcuate ratchet, a snail cam operated by the time piece for determining the setting of the arcuate ratchet to determine the number of blows to be struck at any particular setting by the pivoted hammer, a pivoted link associated with and oscillated by the time piece, a driving pawl carried by the pivoted link and engaging the arcuate ratchet to propel the arcuate ratchet intermittently step-by-step from its set position, a holding pawl for maintaining the arcuate ratchet in position to which it has been moved by the driving pawl, a holding means for the pivoted hammer, and means associated with the holding pawl for intermittently releasing the holding means for the pivoted hammer in accordance with the movement of the 5 ratchet.

3. An improved striking mechanism for a synchronous motor driven time keeping mechanism, comprising a sound emitting device, a pivoted hammer adapted to engage therewith to cause a sound emission therefrom, means for normally holding said pivoted hammer in inoperative position, a snail cam driven by the time keeping mechanism for controlling the setting of the arcuate ratchet to determine the number of blows to be struck by the pivoted hammer, a pivoted link connected to the time piece and oscillated thereby, a driving pawl associated with the pivoted link and positively driving the arcuate ratchet step-by-step, a holding pawl for maintaining the arcuate ratchet in the position to which it has been driven by the driving pawl and for periodically releasing the pivoted hammer in accordance with the movement of the arcuate ratchet, and means driven by the time keeping mechanism for returning the pivoted hammer to normal inoperative position.

4. An improved striking mechanism for a synchronous motor driven time keeping mechanism comprising a sound emitting device, a pivoted hammer adapted to engage therewith, an arcuate ratchet, a snail cam associated with the time keeping mechanism for controlling the setting of the ratchet to determine the number of blows to be struck by the hammer, means for intermittently and positively moving the ratchet step-by-step, a holding pawl for maintaining the ratchet in the position it has been driven by the last named means and for periodically operating the hammer in accordance with the movement of the 45 ratchet.

RALPH MAGRO.
